UNITED STATES PATENT OFFICE.

EDMUND J. WALENTA, SR., OF PHILADELPHIA, PENNSYLVANIA, ASSIGNOR TO STANDARD WALL PAPER CO., OF HUDSON FALLS, NEW YORK.

DESIGN FOR WALL-PAPER.

45,681.

Specification for Design.

Patented Apr. 28, 1914.

Application filed February 12, 1914. Serial No. 818,410. Term of patent 3½ years.

To all whom it may concern:

Be it known that I, EDMUND J. WALENTA, Sr., a citizen of the United States, residing at Philadelphia, in the county of Philadelphia and State of Pennsylvania, have invented a new, original, and ornamental Design for Wall-Papers, of which the following is a specification, reference being had to the accompanying drawing, forming a part thereof.

The figure is a plan view of a section of wall paper showing my new design.

I claim—

The ornamental design for wall paper, as shown.

EDMUND J. WALENTA, SR.
